[57] CLAIM

The ornamental design for a beverage container, as shown and described.

DESCRIPTION

FIG. 1 is a front elevational view of the beverage container showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a left side elevational view in use thereof; and,

FIG. 8 is a top perspective view thereof.

The broken line showing of a portion of a bottle in FIG. 7 is for illustrative purposes only and forms no part of the claimed design.

*FIG. 1**FIG. 2**FIG. 3**FIG. 4**FIG. 5**FIG. 6**FIG. 7**FIG. 8*
